UNITED STATES PATENT OFFICE.

HERBERT E. WHITE, OF YOUNGSTOWN, OHIO, ASSIGNOR TO THE GENERAL FIRE-PROOFING COMPANY, OF YOUNGSTOWN, OHIO, A CORPORATION OF OHIO.

CLIP FOR ATTACHING METALLIC LATH.

1,027,632.

Specification of Letters Patent. Patented May 28, 1912.

Application filed January 31, 1912. Serial No. 674,632.

To all whom it may concern:

Be it known that I, HERBERT E. WHITE, a citizen of the United States, residing in Youngstown, county of Mahoning, State of Ohio, have invented a new and useful Improvement in Clips for Attaching Metallic Lath, of which the following is a specification.

My invention relates to metallic lath fastenings, commonly called "clips" and the object of it is to provide a clip, which can be quickly applied without particular skill.

In the illustrations which are part of this specification like reference characters in the different drawings, refer to the same parts.

Figure 1 is a view in perspective showing the clip in place, illustrating the manner in which it is used to fasten lath to a flange of a beam. Fig. 2 is another view in perspective, illustrating the manner in which the clip is used. Fig. 3 shows the body portion of the clip, illustrating the way in which it is formed out of a piece of sheet metal. Fig. 4 shows a second part or key piece of the clip, this part also being formed out of a piece of sheet metal.

From an inspection of the illustrations any person skilled in the sheet metal working art will understand how to make the improved clip. The body portion D, Fig. 3, is a strip of sheet metal of suitable thickness, say 16 gage, U. S. standard. The blank is bent as shown to form the shoulder C which fits over the rib c of the lath (Fig. 1) and an open slot, 5, is cut to provide means for engaging the flange of a beam. As the shoulder C of the clip is adjusted on the rib of the lath, the arm E of the clip is passed under the flange of the beam. The key piece A is then directed between the flange and the arm E of the clip. A blow from a hammer will then cause the key piece to take the position as shown in Fig. 2.

The key A is made out of a piece of hardened steel having the quality of resiliency necessary for a spring. It will be noticed that the key piece is slightly curved. This is to produce the spring effect, in order that the end portions 3-3, Fig. 4, will press against the flange as shown in Fig. 2. As shown in Fig. 4 one end of the key piece is bent to form the turned edge 2. This is to facilitate the insertion of the key, the turned edge 2 providing a surface which can readily be struck with a hammer. When the key piece is driven into position the groove 1 of the key piece will fit over the edge of the arm E of the body of the clip. The lug 4 and the side 6 of the slot will prevent any lateral movement of the key piece and, as already stated, the spring pressure at points 3-3 when the key piece is in position, will produce a locking engagement, holding the lath rigid and secure to the flange.

What I claim and desire to secure by Letters Patent is—

A clip for attaching metallic lath to a support, consisting of a strip of metal having a portion transversely bent to form a shoulder on one end adapted to engage the rib of a lath, an open slot in the body of the said strip forming an arm, and a key piece consisting of a strip of metal transversely bent to be sprung into position between the said arm and a supporting element, thus bringing the parts in locking engagement.

Signed in the presence of two subscribing witnesses.

HERBERT E. WHITE.
